UNITED STATES PATENT OFFICE.

WILLIAM E. NORTON, OF MINNEAPOLIS, MINNESOTA.

DESIGN FOR A SPROCKET-WHEEL.

SPECIFICATION forming part of Design No. 33,595, dated November 20, 1900.

Application filed October 5, 1900. Serial No. 32,189. Term of patent 7 years.

To all whom it may concern:

Be it known that I, WILLIAM E. NORTON, a citizen of the United States, residing at Minneapolis, in the county of Hennepin and State of Minnesota, have invented and produced a new and original Design for a Sprocket-Wheel; and I do hereby declare the following to be a full, clear, and exact description of the invention, such as will enable others skilled in the art to which it appertains to make and use the same.

In the drawings, Figure 1 is a front view of the sprocket-wheel, and Fig. 2 is a side view of the same.

As shown in the drawings, the leading or material features of the design consist of two concentric circles, the outer of which is provided with teeth, a series of heart-shaped figures interposed between the two said circles,

and a series of diamond-shaped figures interposed between the said heart-shaped figures.

A is the inner circle, and B is the outer circle arranged concentric with the inner circle and provided with teeth b.

C are the heart-shaped figures interposed between the circles A and B, and D represents the diamond-shaped figures interposed between the heart-shaped figures C.

What I claim is—

The design for a sprocket-wheel, as herein shown and described.

In testimony whereof I affix my signature in presence of two witnesses.

WILLIAM E. NORTON.

Witnesses:

W. W. MORSE,
GEO. HAMLEY.
